US0D1076393S

(12) United States Design Patent (10) Patent No.: US D1,076,393 S
(45) Date of Patent: * May 27, 2025

(54) SHOE UPPER

(71) Applicant: Skechers U.S.A., Inc. II, Manhattan Beach, CA (US)

(72) Inventor: John Maxwell Weeks, Playa del Rey, CA (US)

(73) Assignee: Skechers U.S.A., Inc. II, Manhattan Beach, CA (US)

() Term: 15 Years

(21) Appl. No.: 29/918,952

(22) Filed: Nov. 30, 2023

(51) LOC (15) Cl. 02-04

(52) U.S. Cl.

USPC D2/972; D2/969

(57) CLAIM

The ornamental design for a shoe upper as shown and described.

DESCRIPTION

FIG. 1 is a rear perspective view of a shoe upper in accordance with my design;

FIG. 2 is a left side view thereof;

FIG. 3 is a right side view thereof;

FIG. 4 is a top plan view thereof;

FIG. 5 is a front elevation view thereof;

FIG. 6 is a rear elevation view thereof; and,

FIG. 7 is a front perspective view thereof.

The dash-dash broken lines shown in the drawing represent environmental structure of the shoe and form no part of the claimed design.

1 Claim, 7 Drawing Sheets
